ATTORNEY

UNITED STATES PATENT OFFICE.

GEORGE J. MEUER, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

Application filed November 24, 1919. Serial No. 340,212.

To all whom it may concern:

Be it known that I, GEORGE J. MEUER, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

This invention relates to electric switches and more particularly to actuating devices therefor.

In switches employed for the transmission 15 of signals in hospitals and the like it is desirable to provide switch actuating means readily operable by the patient to transmit the signal summoning the attendant, and to provide against subsequent accidental operation of the switch resulting in discontinuation of the call prior to arrival of the attendant.

The present invention has among its objects that of providing actuating mechanism 25 readily applicable to existing switch structures without material alteration thereof for providing the aforementioned operative features.

Another object is that of providing for a 30 push and pull switch having a single operating member, means enabling actuation of such member to operate the switch in either sense from a given location and in one sense only from other locations.

Other objects and advantages will herein-after appear.

In the accompanying drawing wherein is illustrated an embodiment of the invention, Figure 1 is a side elevational view thereof; 40 while

Fig. 2 is a perspective view illustrating certain details.

Referring to the drawing, the same illustrates a switch mechanism indicated generally at 1 having a single push and pull operating member 2. Said switch mechanism is adapted to flush mounting within an ordinary outlet box having a face plate 3 and to such end is provided with lugs 4 and 5 formed integral with or rigidly secured to a front plate 6 of the switch and adapted to receive suitable screws for securing the switch within the outlet box and also securing the face plate in position in the usual manner. Said lugs are further provided

with offset portions 7 and 8 serving to space the switch inwardly away from the face plate a sufficient distance to permit full reciprocation of the operating member 2 without restraint by said face plate.

The projecting portion of the operating member is reduced to provide a shoulder 9 and is terminally screw threaded to receive a nut 10. A yoke 11 is mounted upon said reduced portion of the operating member, 60 being clamped against the shoulder 9 by means of the nut 10. A push button member 12 is riveted or otherwise rigidly secured to the upper end of said yoke and adapted to extend through a suitable opening 13 in the 70 face plate 3 to provide for actuation of the switch in one sense only. The opposite end of said yoke is bent to provide a shallow transverse groove 14 and is further provided with a longitudinal slot 15 the 75 inner end of said slot having an enlarged portion 16 coinciding with said groove and adapted to receive the terminal portion of a chain 17 or other suitable flexible connection extending through a second opening 18 in 80 said face plate to provide for actuation of the switch in the opposite sense only.

A hollow internally tapered horn or guide 85 19 is riveted or otherwise rigidly secured within the opening 18 of said plate to surround the chain 17 for facilitating traverse of the latter through the plate and insuring a substantially straight pull upon the yoke irrespective of the angle from which the pull upon the chain is exerted. The push 90 button 12 is further adapted to coact with the sides of the opening 13 for guiding the movable switch parts and insuring rectilinear motion thereof under all conditions of operation and particularly when actuated by 95 a pull upon the chain.

In practice the last link of the chain 17 is slipped through the contracted portion of the slot 15 and located within the enlarged portion thereof, the sides of the yoke adjacent said contracted portion of the slot being thereafter sprung inward to prevent withdrawal of the chain.

The manner of operation of the aforescribed mechanism may be briefly outlined 105 as follows; assuming the switch to be so connected as to control the transmission of call signals in a hospital or the like, the chain extending within easy reach of the patient and being the only element within 110

the patient's control. A single slight pull upon the chain serves to operate the switch in the appropriate sense for initiating the call signal, whereas subsequent actuation of the chain produces no further effect upon the switch, whereby such signal will continue to be transmitted pending actuation of the switch in the opposite sense by means of the push button which will ordinarily occur only upon arrival of the attendant, whereupon the switch is again subjected to control by the patient by means of the chain in the manner aforescribed.

What I claim as new and desire to secure by Letters Patent is:

1. The combination with an electric switch having a single push and pull operating member, of associated devices each providing for actuation of said operating member in one direction only, certain of said devices being operable from locations remote from said switch.

2. The combination with an electric switch having a single push and pull operating member, of associated devices each providing for actuation of said operating member in one direction only, certain of said devices being operable from a given location only and other of said devices being operable from other locations.

3. The combination with an electric switch having a single push and pull operating member, of associated devices each providing for actuation of said operating member in one direction only, all of said devices being operable from a given location and certain only of said devices being operable from other locations.

4. The combination with an electric switch having a single push and pull operating member, of associated devices each providing for actuation of said operating member in one direction only, certain of said devices being operable from locations remote from said switch, and all of said devices being operable from a given point adjacent said switch.

5. The combination with an electric switch having a single push and pull operating member, of a yoke secured to said operating member, a push button and a pull chain secured to said yoke to provide for actuation of said operating member in opposite directions respectively.

6. The combination with an electric switch having a single push and pull operating member, of associated devices each providing for actuation of said operating member in one direction only, certain of said devices being operable from locations remote from said switch, and means coacting with certain of said devices for guiding said operating member during movement thereof.

7. The combination with an electric switch having a single push and pull operating

member, of associated devices each providing for actuation of said operating member in one direction only, certain of said devices being operable from locations remote from said switch and means coacting with certain of said devices for guiding said operating member during actuation thereof by other of said devices.

8. The combination with an electric switch adapted to flush mounting, in conjunction with a face plate, said switch having a push and pull operating member located rearwardly of said plate, of associated devices connected with said operating member and penetrating said plate, each of said devices providing for actuation of said operating member to operate the switch in one sense only.

9. The combination with an electric switch having a push and pull operating member and adapted to flush mounting, in conjunction with a face plate, of means for mounting said face plate upon said switch forwardly of and in spaced relation to said operating member and associated devices connected with said operating member and extending through and forwardly of said plate to provide individually for actuation of said operating member in one direction only.

10. The combination with an electric switch having a push and pull operating member and adapted to flush mounting, in conjunction with a face plate, of means for mounting said face plate upon said switch forwardly of and in spaced relation to said operating member and associated devices connected with said operating member and extending through and forwardly of said plate to provide individually for actuation of said operating member in one direction only, certain of said devices being operable from points remote from said switch.

11. The combination with an electric switch having a push and pull operating member and adapted to flush mounting, in conjunction with a face plate, of means for mounting said face plate upon said switch forwardly of and in spaced relation to said operating member and associated devices connected with said operating member and extending through and forwardly of said plate to provide individually for actuation of said operating member in one direction only, one of said devices having a portion adapted to coat with said plate for guiding said operating member when actuated by another of said devices.

12. The combination with an electric switch having a push and pull operating member and adapted to flush mounting, in conjunction with a face plate, of means for mounting said face plate upon said switch forwardly of and in spaced relation to said operating member and associated devices connected with said operating member and

extending through and forwardly of said plate to provide individually for actuation of said operating member in one direction only, said plate having means for guiding 5 both of said devices.

13. The combination with an electric switch having a push and pull operating member and adapted to flush mounting, in conjunction with a face plate, of means for 10 mounting said face plate upon said switch forwardly of and in spaced relation to said operating member and associated devices connected with said operating member and extending through and forwardly of said 15 plate to provide individually for actuation of said operating member in one direction only, said plate having means for guiding both of said devices and insuring rectilinear movement of said operating member when 20 actuated by either of said devices.

14. The combination with an electric switch adapted to flush mounting, in conjunction with a face plate and having a push and pull operating member located 25 rearwardly of said plate, of a yoke secured to said operating member, a push button secured to said yoke and projecting through said plate to provide for actuation of said

operating member in one direction and to guide said member during movement thereof and a flexible member penetrating said plate and connected to said yoke to provide for actuation of said operating member in the opposite direction. 30

15. The combination with an electric switch adapted to flush mounting, in conjunction with a face plate and having a push and pull operating member located rearwardly of said plate, of a yoke secured 35 to said operating member, a push button secured to said yoke and projecting through said plate to provide for actuation of said operating member in one direction and to guide said member during movement thereof and a flexible member penetrating said plate 40 and connected to said yoke to provide for actuation of said operating member in the opposite direction, said plate having guiding means for transmitting a pull substantially parallel to the axis of said operating 45 member irrespective of the direction of force applied to said flexible member. 50

In witness whereof, I have hereunto subscribed my name.

GEORGE J. MEUER.
